UNITED STATES PATENT OFFICE.

SYDNEY JUHN, OF BALTIMORE, MARYLAND, ASSIGNOR TO VARSITY UNDERWEAR COMPANY, OF BALTIMORE, MARYLAND, A CORPORATION OF DELAWARE.

UNION SUIT.

1,090,155.

Specification of Letters Patent. Patented Mar. 17, 1914.

Original application filed July 26, 1913, Serial No. 781,317. Continuation of application filed January 21, 1914. Serial No. 813,370.

To all whom it may concern:

Be it known that I, SYDNEY JUHN, a citizen of the United States of America, residing at 1727 Madison avenue, city of Baltimore, State of Maryland, have invented certain new and useful Improvements in Union Suits, of which the following is a specification.

The invention relates to a one-piece undergarment or union suit, and particularly to a garment having a rear flap opening and permanently closed crotch.

This application is a continuation of my application No. 781,317, filed July 26th, 1913, showing the same garment.

Union suits with the closed crotch have been offered to the trade and are now in use, but they are objectionable because of the unsightly and inconvenient fullness of the crotch which is a necessary feature of the previous construction. This defect is more marked when the suit is constructed of non-elastic material of the kind now largely used in the manufacture of light-weight underwear as nainsook and similar materials, than it is in the case of the more elastic knit fabrics, and the present invention is particularly applicable to garments constructed of non-elastic materials, though other materials may be used within the scope of the invention.

To overcome the difficulty referred to and produce a new, improved and perfectly fitting garment with a posterior flap opening conveniently operable and providing the necessary degree of accessibility, is the object of my invention.

I am aware of the existence of the Johnson Patent No. 793,200 and of the fact that various garments differing from the one shown in this patent to a slight degree are on sale. These latter garments are unlike that of the Johnson patent principally in that the point "i" of the flap "L" is removed so that the flap opening extends down to the inseam on the right. On the left the seam which joins the seat-piece or rear flap to the left rear section of the garment, in both instances extends down to the inseam, the seat-piece or rear flap thus formed being a single piece of material having two depending points extending down the legs. Referring to this in the terms of the ordinary trousers garment, both the rear sections are cut away on the side where the cen-

ter rear seam should be to provide room for the rear flap which covers a considerable area on both sides of the center of the rear of the garment. As distinguished from this the applicant in the preferred form of his invention has evolved a garment in which, referring particularly to the lower or trousers portions, three sections of the pattern, i. e., the front and one, preferably the left, rear section, are similar in form to the corresponding sections of the ordinary trousers garment or underdrawers, except that the inseam is thrown well forward, the front sections being cut away and the rear sections increased correspondingly to achieve this result and at the same time give the garment the same fit which it would have if cut in the ordinary manner with the closed crotch and without the rear flap opening.

The right rear section is made in two parts, a right rear section proper but cut away to form a rear flap opening, and a flap which is joined to the left rear section along the central rear seam from the waist as far as the crotch point and to the front section on the right from the crotch point for a few inches down the inseam. The other or free edge of this flap is curved outward centrally and extends from the crotch seam upward to the center seam, the top of the flap being preferably joined to the waistline of the garment. The right rear section is cut away to form an opening corresponding to the flap, but otherwise is similar in shape to the corresponding portion of the left rear section. In fact, in the preferred embodiment of the invention the two parts of the right rear section when laid together in normal relation, are identical in form with the left rear sections.

It is important to note that the rear sections, the left rear section being a single piece and the right rear section formed of the flap, and a co-operating piece, which when placed in their operative relation, form a pattern similar to the left rear section, are similar in outline to the corresponding portions of the usual trousers garment except that the points of the pattern which meet at the crotch point, are elongated and the leg portions are slightly widened, the extra material thus provided being turned forward and compensated for by a corresponding reduction of the front sections. In this way an improved fitting

effect is obtained and the flap opening is elongated so that it extends well forward around the curve of the leg, and by the construction thus obtained, the flap is caused to open and swing in a convenient manner which will be apparent from inspection of the drawing. The peculiar accessibility aside from the extra length of the flap opening which results from moving the inseam forward, is due to the pointed effect in the rear of the garment obtained by elongating the crotch point ends of the rear sections, giving the meeting edges at the rear seam a sharp rearward curve. The point thus formed disappears when the garment is worn in the ordinary manner, but when the flap is open, it in effect turns inside out and swings the flap opening inward toward the center of the garment.

20 The drawing illustrates a union suit constructed in accordance with my invention in its preferred form.

Figure 1 is a front elevation. Fig. 2 is a rear elevation. Fig. 3 is a plan. Fig. 4 shows the rear sections separated. Fig. 5 is a view showing the rear flap opened, the point formed by turning in the rear sections being turned inside out to swing the opening to the center. Fig. 6 is a fragmentary view showing the right half of the garment folded on a central longitudinal plan the left half being removed. This is the garment as it would hang if suspended by the top corners of the rear section, the front sections being folded in.

Referring to the drawing by numerals, each of which is used to indicate the same or corresponding parts in the different figures: the garment illustrated is formed of 40 pieces of non-elastic material, though the number of pieces in the general pattern may be varied, and elastic or knitted material may be used within the scope of my invention. There are two front sections 1 forming the front of each leg and the corresponding half of the upper portion of the garment, a rear section 2 on the left side of the garment forming the rear side of the left leg below the waistline, a right rear section 3 similar to the section 2 but cut away on the dotted lines 4 leading from a point 5 on the waistline to the crotch or inseam 22 on the inside of the right leg at 6 three or four inches from the crotch point, thus forming an opening to be covered by the rear flap 7. This flap in its preferred form extends from the center of the waistline at 5 to the crotch point 9, being joined to the left rear section 2 throughout the length of the rear seam 10 which is curved sharply outward and turned in as herein-after described. The top edge of the rear flap 7 from the point 5 to the point 8 is sufficiently long to give the necessary overlap to the closure. It is sewed to the waist-

seam 11 and the bottom edge 12 is joined to the front right section 1 along the inside or crotch seam from the crotch point 9 to the point 6. Thus the rear flap 7 which as shown and in its preferred form is a four-sided section, is fastened on three sides and has a free swing as to the fourth side 13 which is preferably curved outward from top to bottom, the peak being near the center, and fastened by any suitable means 75 as a button and buttonhole 14.

In the form of the invention shown the sixth section consists of a single piece 15 forming the back of the top portion of the garment, though this is in nowise related to the invention and the construction of the entire garment except as to the crotch and rear opening, may be widely varied without departure from the invention and any material may be used.

80 In the garment shown the top section 15 is joined to the rear sections 2 and 3 by means of an elastic band 16 which may be of knit or any similar or suitable elastic material. This is to give elasticity to the garment and 90 freedom of movement to the wearer.

Referring to Fig. 4, the peculiar construction of the rear sections will be noted. The left rear section which as shown is a single or rather flat piece of material, is given an 25 excessive curve as to the rear seam line 17, as will be understood from Fig. 4, and this seam and the crotch point 18 of the rear section are elongated to an extent represented by the line 18, 19, and this section is 100 increased adjacent the inseam 22 to an extent represented by the distance between the line 22 and the line 20 of Fig. 4. In this way the inseam is thrown well forward, the front sections being reduced, as 105 shown at 21, 22 in Fig. 1, to conform to the increase of the rear section, the edges 23 of the rear sections and flap, see Fig. 4, being turned forward and forming in effect a portion of the front of the garment. The 110 rear of the garment is thus given when hanging loose, the pointed effect illustrated in Fig. 6, the point disappearing when the garment is worn and the middle portion of the rear seam is turned outward to conform to the body but tending to turn inside out and throw the flap opening over toward the center of the garment when the rear flap is open as shown in Fig. 5. This is an 115 eminently desirable result and one which is 120 not incident to and cannot be obtained with the usual flat-seat-piece extending on both sides of the rear of the garment, as will be easily understood by those familiar with the art.

125 I have thus described specifically and in detail a single embodiment of my invention in order that its nature and operation may be clearly understood. However, the specific terms herein are used in their descrip- 130

tive rather than in their limiting sense and the scope of the invention is defined in the claims.

I claim—

- 5 1. A closed crotch union under garment having a rear section and a rear flap meeting and secured together on a vertical median line, a rear section cut away to form a rear opening, the rear flap and the last
- 10 mentioned rear section thus cut away, together forming a section similar in outline to the first mentioned rear section, the rear median seam edges of both sections being curved outward sharply at the bottom, the
- 15 inseam edges of both sections being extended and the garment having front sections with inseam edges correspondingly cut away to move the crotch or inseam well forward, the front sections being seamed together on a median line at the lower portion of the front, and the flap being secured to the front section on the same side along the inseam from the crotch point down to the free edge of the flap, so that when
- 20 the garment is hanging free, the rear median seam curves outward to a point, at which point the rear sections are turned inward to the crotch or inseam, the rear flap opening extending from a point well up
- 25 the back around the curve of the leg to the inseam at a point well below the crotch point, so that the flap is wholly on one side

of the rear median seam and when the rear flap is opened and swung to the left, the point referred to thus formed by the curvature of 35 the rear seam, turns inside out and swings the opening to the middle of the garment.

2. A permanently closed crotch union undergarment provided with a rear opening, said garment comprising front and rear 40 portions, one half of one rear section extending to the vertical median line and the opposite rear section cut away from said median line, a rear flap having one edge sewed to the first mentioned rear section 45 along such median line from a point near the waistline downwardly through the crotch and upwardly a short distance on the front of the garment and thence downwardly along the inseam of one leg, the opposite edge of such flap being free, the free edge extending from a point near the waistline to a point on the inseam of the leg a considerable distance below the apex of the 50 crotch whereby such flap extends from the 55 vertical median line to one side only of such garment.

Signed by me at Atlantic City N. J. this 16 day of January 1914.

SYDNEY JUHN.
